United States Patent Office

Des. 197,183
Patented Dec. 24, 1963

197,183

CLOCK

Charles A. McLeod, Evanston, Ill., assignor to Sunbeam Corporation, Chicago, Ill., a corporation of Illinois

Filed June 14, 1963, Ser. No. 75,348

Term of patent 14 years

(Cl. D42—7)

FIG. 1 is a front elevational view of a clock embodying my new design; and

FIG. 2 is a bottom plan view thereof.

I claim:

The ornamental design for a clock, as shown.
